UNITED STATES PATENT OFFICE.

JOHN R. MITCHELL, OF NEW YORK, N. Y., ASSIGNOR TO MITCHELL-BISSELL CO., OF NEW YORK, N. Y., A CORPORATION OF NEW JERSEY.

GUIDE.

No. 852,073.

Specification of Letters Patent.

Patented April 30, 1907.

Application filed January 8, 1907. Serial No. 350,654.

To all whom it may concern:

Be it known that I, JOHN R. MITCHELL, a citizen of the United States, residing at New York, county of New York, State of New York, have invented certain new and useful 5 Improvements in Guides, of which the following is a specification.

My invention relates to guides for guiding thread, yarn etc. in spooling and other machines, and consists of a block having certain overlapping fingers with notches and lips and separated by a diagonal slot, as fully set forth hereinafter and illustrated in the accompanying drawing in which—

Figure 1 is a plan of my improved guide; and Fig. 2, an end view.

The guide consists of a block A adapted for attachment to a metallic support B, as for instance a bar fitting a socket of the block 20 the latter preferably of porcelain or other material having a smooth polished surface.

The block is divided at the outer end by a slot x, extending in a diagonal direction and leading back to an opening y, extending vertically through the block, thus forming two fingers a, b, the forward ends of which overlap laterally, and at the inner part of each finger is a lip 2, forming with the other part of the finger a notch u, the two notches there- 30 fore being in separated positions vertically.

The block is arranged horizontally in use,

and in threading a yarn through the same it is carried to a diagonal position so as to pass through the slot x into the opening y. So long as there is no extended lateral motion 35 imparted to the yarn it will be retained in vertical position by the sides of the opening y, but if it is drawn forward the inclined face v of the finger toward which it is carried will deflect the yarn toward the opposite finger, 40 and any further forward movement will carry the yarn into one or the other notch u so that it cannot possibly escape.

It will be evident that the proportions of the guide may be changed without departing 45 from the main features of my invention.

I claim—

A guide consisting of a block having a vertical central opening, and a slot extending in a diagonal direction from said opening to 50 the outer end of the guide forming overlapping fingers, and a lip 2 on the inner part of each finger forming a notch u between the lip and the body of the finger, as and for the purpose set forth.

In testimony whereof I affix my signature in presence of two witnesses.

JOHN R. MITCHELL.
